UNITED STATES PATENT OFFICE.

JOHN WILSON BROWN, JR., OF PHILADELPHIA, PENNSYLVANIA.

DESIGN FOR A CROSS-BAR FOR SAD-IRONS.

SPECIFICATION forming part of Design No. 25,520, dated May 19, 1896.

Application filed October 10, 1895. Serial No. 565,294. Term of patent 14 years.

To all whom it may concern:

Be it known that I, JOHN WILSON BROWN, Jr., a citizen of the United States, residing in Philadelphia, Pennsylvania, have invented 5 a certain new and useful Design for the Cross-Bars of Sad-Iron Handles, of which the following is a specification.

My design for the cross-plate of a sad-iron handle is fully illustrated in the accompanying drawings, in which—

Figure 1 is a plan view. Fig. 2 is an inverted plan view. Fig. 3 is a side view. Fig. 4 is a longitudinal sectional view, and Fig. 5 is a transverse sectional view.

15 The essential features of the design of the plate are the plain top, the enlargements at each end, and downwardly-extending ribs at each side.

A is the plate, having downwardly-extending ribs α at each side, the edges of the

plate being slightly rounded. On each end of the plate are circular enlargements a' , having inclined upper faces, as shown in Fig. 3. At the center of the plate is an opening b of the shape shown, and depending from the under side of the plate is the inclined tongue b' , giving the appearance to the plate as clearly indicated in the drawings.

I claim—

The design for a cross-plate of a sad-iron 30 handle as described and as shown in the accompanying drawings.

In testimony whereof I have signed my name to this specification in the presence of two subscribing witnesses.

JOHN WILSON BROWN, JR.
